UNITED STATES PATENT OFFICE.

CARL OTTO, OF SAGINAW, MICHIGAN, ASSIGNOR TO SONORA PHONOGRAPH COMPANY, INC., A CORPORATION OF NEW YORK.

DESIGN FOR A COMBINATION RADIO AND PHONOGRAPH CABINET.

Application filed November 13, 1928. Serial No. 28,862. Term of patent 7 years.

To all whom it may concern:

Be it known that I, CARL OTTO, a citizen of the United States of America, residing in Saginaw, county of Saginaw, State of Michigan, have invented a new, original and ornamental Design for Combination Radio and Phonograph Cabinets, of which the following is a specification, reference being had to the accompanying drawing, forming a part thereof.

This figure is a perspective view of a combination radio and phonograph cabinet illustrating my new design.

I claim:

The ornamental design for a combination radio and phonograph cabinet substantially as shown.

This specification signed this 7th day of November, 1928.

CARL OTTO.
